FOUNTAIN FEED DIP PEN

Hugo A. Funk, Los Angeles, Calif., assignor of
one-half to Lena Latham Goble, Los Angeles,
Calif., and one-half to N. C. Funk, Hermosa
Beach, Calif.

Application May 22, 1934, Serial No. 726,980

10 Claims. (Cl. 120—113)

My invention relates broadly to pens and more particularly to a fountain feed dip pen.

One of the objects of my invention is to provide an inexpensive construction of fountain feed dip pen which is simple in its construction and capable of manufacture on a quantity production basis at a low cost.

Another object of my invention is to provide a construction of fountain feed dip pen having means for retaining a quantity of ink and means for feeding the ink to the pen point throughout the writing operation.

Still another object of my invention is to provide a construction of fountain feed dip pen having a readily renewable writing point.

A further object of my invention is to provide a construction of fountain feed dip pen including a feed member of non-breakable material such as pyralin.

A still further object of my invention is to provide a construction of fountain feed dip pen in which the feed includes a spring member for performing the dual function of eliminating variations in shrinkage and expansion of the material and also providing a capillary feed for ink to the pen point.

A further object of my invention is to provide a construction of renewable spring member co-acting with an ink retaining member adjacent the pen point, the spring being designed for removably securing the pen point in position while compensating for variations in shrinkage and suspension of the material and simultaneously serving as a capillary feed for ink to the pen point.

Other and further objects of my invention reside in the construction of fountain feed dip pen and removable spring member associated therewith, as set forth more fully in the specification hereinafter following by reference to the accompanying drawing, in which:

Figure 1 is a fragmentary side elevation on an enlarged scale of the forward end of a writing pen constructed in accordance with my invention; Fig. 2 is a central, vertical longitudinal section thereof; Fig. 3 is a side elevation with the writing pen removed from the reservoir and in juxtaposition; Fig. 4 is a plan view thereof; Figs. 5, 6 and 7, are transverse sections on corresponding lines designated in Fig. 2; Fig. 8 is a detail side elevation of the ink reservoir; Fig. 9 is a plan view thereof; and Fig. 10 is a detail perspective view of feed wire supplying the desk writing pen with ink from the reservoir.

I have developed the fountain feed dip pen of

my invention for facilitating continuous writing with ink while reducing the necessity of frequent dipping of the pen and without the necessity of providing a fountain pen. Where it is necessary to provide large numbers of writing pens in a business organization, the purchase of fountain pens becomes a substantial and sometimes impractical investment. I have found the fountain feed dip pen of my invention highly practical for purposes of writing over a relatively long period of time and with only infrequent dipping of the pen into the ink supply. The pen point is readily renewable which is a marked advantage over the usual types of fountain pens.

With the pen of my invention, I have found that the automatic filling of the pen with each dip in

the ink supply is sufficient for the writing of approximately 1000 words without dipping, the ink always flowing evenly from start to finish. I pro-

vide a pen holder equipped to receive a plug member of molded material such as a cellulose product. I have used with considerable success the material pyralin. The plug member formed from cellulose product is slotted longitudinally with the slots disposed in planes normal one to the other.

One of the longitudinal slots serves as a seat for a spring member. The other of the longitudinal slots serves as a reservoir for ink. The slots are interconnected and a spring member inserted in one of the slots. The spring member operates to

compensate for shrinkage and variations in the material and to continuously engage the pen point which is inserted in the pen holder. The spring member also serves as a capillary feed for ink

retained in the reservoir which ink is continuously supplied to the pen point mounted in the pen holder. The pen point may be readily renewed from time to time. All of the advantages of a fountain pen may be obtained without the cost and many disadvantages of such fountain pens.

There is substantially no fixing or repair required in the fountain feed dip pen of my invention. The pen point costs but a few cents to replace. It is not necessary to shake the pen to start the ink for the ink always flows lightly and evenly.

The pen of my invention coacts with a desk set in the form of an ink supply receptacle in which the pen point is adapted to be submerged when not being used for writing purposes. During such times, the pen is not simply idle. It is, in fact, filling itself by capillary feed of ink into the slots provided in the plug member adjacent the pen point ready for instant use for writing purposes.

Referring to the drawing in detail, reference character 1 designates a pen holder which is recessed at 2 to receive the sleeve member 3. The sleeve member 3 has an exterior surface formed by cylindrical portion 4 and a tapered portion 5. The end of the sleeve 3 is chamfered as at 6 to contact with a similarly chamfered portion 2a of the recess on socket 2. The sleeve 3 is apertured at 7 at one side thereof to allow a small deposit of glue or cement to be employed for securing the sleeve 3 in position in socket 2. The interior wall of sleeve 3 is cylindrical and provides a recess into which the pyralin plug 8 is inserted. The pyralin plug is shaped, as shown more particularly in Figs. 8 and 9, to include the substantially cylindrical portion 9 and a nib supporting portion 10. The pyralin plug 8 is provided with a pair of longitudinally extending slots which extend in planes normal to each other. 10 One of these slots is shown at 11 and forms the ink retaining means for the pen. The other slot is shown at 12 and extends beyond the limits of slot 11 in the nib supporting portion of the plug and terminates short of the extremity of the 15 plug which is inserted in the socket 2, as illustrated more particularly in Fig. 2. There are ink feed channels on opposite sides of plug 8 which connect the slots 11 and 12 around the exterior surfaces of the plug 8, as shown at 14. 20 One of these recesses 15 which serve to facilitate the feeding of ink to the pen point. It will be observed that slot 12 extends to within a relatively thin wall thickness 16 of the nib supporting portion 10 of the plug 8. The shape of the plug 8 is such that pen point 17 may be inserted into the narrow arcuate shaped space 18 which is left in between a semicylindrical portion of plug 8 and the interior cylindrical surface of sleeve 3. This 25 space is provided because of the compression to which the two halves of the plug are subjected. The two halves of the plug perform a dual function, that is, they serve as a grip for the spring member 20 and as a means for retaining the 30 plug 8 in the socket 2.

The pen point 17 is wedged into the arcuate shaped space 18 by insertion between the exterior surface of the plug and the interior surface of sleeve 3 and is secured more firmly in position by 35 means of the resilient engagement of the spring member 20 therewith.

The spring member 20 is shown more clearly in Fig. 10. The member comprises a wire bent upon itself having arms 20a and 20b. Arm 20b is extended through the slot 11. Arm 20a extends through slot 12. Arm 20a is bent to include a portion 20c which conforms with the recess 15 in plug 8. The wire member 20 has a bowed portion which contacts with the undersurface of the pen point 17 and particularly at the position 17a of the pen point where the slit in the pen point terminates. The portion 20a of the resilient member 20 which bears against the undersurface of the pen point 17 tends to force the point into 40 closer frictional engagement with the interior cylindrical surface of sleeve 3.

Spring member 20 serves as a capillary feed for ink retained in slots 11 and 12 for delivering ink continuously to the pen point. The resilient member 20 so coacts with the channels 14 and the recesses 15 in plug 8 that a continuous feeding of ink is effected from slots 11 and 12 to the pen point. The size of slots 11 and 12 is such that a substantial quantity of ink may be retained at 45 each dipping operation.

I have found the pen of my invention highly practical in its manufacture, production, and operation and, while I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. A pen comprising a holder having a socket in one end thereof, a sleeve member mounted in said socket, a plug insertable in said sleeve member, said plug terminating in a pen supporting portion and having longitudinally extending slots disposed at an angle with respect to each other, one of said slots terminating short of the other of said slots, a hook shaped member having the longer arm thereof gripped in the longer of said slots beyond the termination of the shorter slot, and a pen point mounted on said plug in contact with the shorter arm of said hook shaped member and retained between a portion of said plug and the interior wall of said sleeve.

2. A pen comprising a pen holder, a plug mounted in said pen holder, a pen point mounted with respect to said plug, said plug having a pair of longitudinally extending slots therein, and a bowed member disposed in said slots and connected with said pen point for establishing a capillary feed path for ink to said pen point.

3. A pen comprising a holder, a plug carried by said holder, a pen point mounted with respect to said plug, a pair of slots disposed in said plug, and a resilient member bent upon itself and having one arm thereof clamped in one of said slots and having the free arm thereof contacting with said pen point and establishing a capillary feed path for ink from said slots to the pen point.

4. In a pen, a pen holder, a plug mounted in said pen holder, a pen point supported by said plug, said plug having a pair of longitudinally extending slots therein disposed normal to each other, and a resilient hook shaped member extending through each of said slots and contacting with said pen point and establishing a capillary feed path for ink from said slots to said pen point.

5. In a pen, a pen holder, a plug mounted in said pen holder, a pen point supported by said plug, said plug having a pair of longitudinally extending slots therein disposed normal to each other, and a wire member bent upon itself, said wire member having one arm thereof gripped within one of said slots and having the other arm thereof yielding engaged against said pen point, said wire member establishing a feed path for ink from said slots to said pen point.

6. A pen comprising a pen holder having a socket in one end thereof, a sleeve member mounted in said socket, a plug, said plug having a longitudinally extending slot therein for rendering diametrically opposite portions of said plug displaceable inwardly for facilitating the insertion of said plug in said sleeve, a pen point mounted with respect to said plug and secured between a cylindrical portion of said plug and the interior wall of said sleeve, a second slot extending longitudinally of said plug at an angle to the aforesaid slot, and a wire member bent upon itself and extending through each of said slots, said wire member engaging said pen point and establishing a capillary feed path for ink from said slots to said pen point.

7. A pen comprising a pen holder having a

socket in one end thereof, a sleeve member mounted in said socket, a plug, said plug having a longitudinally extending slot therein for rendering diametrically opposite portions of said plug displaceable inwardly for facilitating the insertion of said plug in said sleeve, a pen point mounted with respect to said plug and secured between a cylindrical portion of said plug and the interior wall of said sleeve, a second slot extending longitudinally of said plug at an angle to the aforesaid slot, and a wire member bent upon itself having one arm longer than the other, the longer arm extending between the displaceable portions of said plug and rigidly gripped thereby and the shorter arm yieldably engaging said pen point and providing a capillary feed path for ink from said slots to said pen point.

8. A pen comprising a holder, a plug mounted in said holder, said plug having a pair of longitudinally extending slots therein with one of said slots extending at an angle with respect to the other of said slots, channelways formed on the exterior surface of said plug and interconnecting said slots, a pen point mounted with respect to said plug, and a bowed member disposed in said

slots and contacting said pen point for facilitating the feeding of ink to said pen point.

9. A pen comprising a pen holder, a plug carried by said pen holder, said plug having a pair of longitudinally extending slots therein, said slots being interconnected centrally of said plug, a recess in said plug adjacent one junction of one of said slots with the exterior surface of the plug, a pen point mounted with respect to said plug, and a wire member extending through said slots and through the recess adjacent one of said slots and yieldably engaging said pen point and establishing a capillary feed path for ink between said slots and said pen point.

10. A pen comprising a holder, a plug adapted to be mounted in said holder, said plug having a pair of slots extending longitudinally therein, said slots being interconnected with each other centrally of said plug, a pen point mounted with respect to said plug and a substantially V-shaped spring wire confined within said slots and yieldably engaging the said pen point for establishing a capillary feed path for ink between said slots and said pen point.
